UNITED STATES PATENT OFFICE.

GEORGE M. DANIELS, OF QUINCY, MASSACHUSETTS.

COVER-HOLDER FOR BOOKS.

1,246,243.

Specification of Letters Patent. Patented Nov. 13, 1917.

Application filed October 18, 1916. Serial No. 126,313.

To all whom it may concern:

Be it known that I, GEORGE M. DANIELS, a citizen of the United States, residing at Quincy, in the county of Norfolk and State of Massachusetts, have invented new and useful Improvements in Cover-Holders for Books, of which the following is a specification.

The object of the present invention is to provide an improved cover-holder for books, to which the books may be readily attached and from which they may be detached. The term "books", as used for the purposes of the following description and claims, is used in its broad sense, to include catalogues, magazines, and pamphlets, without regard to whether such elements are provided with stiff covers or not.

My present device is adapted to hold a plurality of books at one time, and is not restricted as to the size of such books, being capable of holding books of different size at the same time. The device comprises a cover element and metal clips, the latter being detachable and adapted to hold the books in the desired position in the cover element. Each clip is formed with a hump that is arranged to coact with a strap carried by the cover element, and the function of such hump is to prevent the clip from being accidentally displaced or detached from the strap to which the clip is applied.

Of the accompanying drawings, which illustrate the invention:

Figure 1 represents a perspective view showing the cover element partly open and four books attached thereto.

Fig. 2 represents a face view of the inside of the cover element, the latter being open and in a substantially flat condition.

Fig. 3 represents a cross section, on a larger scale, through structure intersected by line 3—3 of Fig. 2.

Fig. 4 represents a sectional view, in a plane from top to bottom, of the cover element and a book of maximum height fastened therein by detachable clips, the broken lines indicating that a portion of the assemblage is omitted to save space on the drawing.

Fig. 5 represents a view similar to Fig. 4 excepting that the cover element is omitted and a book of relatively small size is secured to the anchoring straps.

Fig. 6 is a view similar to Fig. 5, excepting that a book of intermediate size is represented.

Fig. 7 represents an elevation of a detachable clip having a hump arranged to hold it against accidental detachment.

Fig. 8 represents a similar view of a clip having a hump of a different shape.

The same reference characters indicate the same parts wherever they occur.

The cover element comprises a back 10, hinged leaves 11, 11, and flexible hinge elements 12 connecting the leaves with the back. The back is preferably provided with a stiffening strip 13 and is preferably curved as indicated in Figs. 1 and 3. The cover element is provided with a plurality of straps 14, of which at least two are necessary. When only two straps are provided they would preferably be arranged near the upper and lower edges 15 and 16, respectively, of the cover element. However, in order to enable the cover element to hold books of different heights, I provide an additional strap or straps 14'. These straps extend transversely across the inside of the back 10, and their end portions are preferably arranged against and glued to the outer surface of the stiffening member 13, as shown by Fig. 3. The intermediate portion of each strap is loose relatively to the cover element. The term "loose" does not mean a slack condition, but means a condition of freedom as to separation from the back. See Fig. 3. As a matter of fact, I prefer to have the intermediate portion of the strap tight, so that it will preserve the arched or curved formation of the back and also preserve a suitable space between it and the back for the reception of the clips hereinafter described.

The straps 14, 14' afford anchorage for a plurality of detachable clips, and the latter are used to secure the books in the cover element. Each clip is made of a piece of spring-metal wire and has two legs, 17, 18, and a portion 19 connecting them. One leg of each clip, in the present instance the leg 17, has a hump projecting toward the other leg. In the form shown by Fig. 7 the hump is indicated at 20, and in the form shown by Fig. 8 it is indicated at 20'. Both forms are, to all intents and purposes, equivalents excepting that that shown by Fig. 8 is

more abrupt on one side than on the other, to make detachment from the strap more difficult.

As shown by Fig. 1 there are four books secured to the cover element, and they are indicated respectively at 21, 22, 23, and 24. Each book is held by two clips, as shown by Fig. 4. In the latter figure the height of the book is commensurate with the distance between the upper edge of the upper strap 14 and the lower edge of lower strap 14. Each clip shown in Fig. 4 embraces a strap 14 and the back of the book, the legs 18 of the clips being arranged between two contiguous leaves of the book as illustrated by Fig. 1. The hump 20 of the upper clip coacts with the lower edge of the upper strap 14, and the corresponding hump of the lower clip coacts with the upper edge of the lower strap 14. The clips are formed so that the legs normally converge as shown by Figs. 6, 7 and 8, so that it is necessary to spring the legs apart in order to apply the clips as shown. The tendency of the legs to spring toward each other maintains the humps in coercive relation to the said edges of the straps 14, and the clips are thus held in the desired position relatively to the straps and book. A book having a relatively short measurement from top to bottom, such as the book indicated at 25 in Fig. 5, could be secured in the cover element by applying the clips to the straps 14' instead of to the straps 14, and in like manner a book of intermediate height, such as that indicated at 26 in Fig. 6, could be secured in the cover by applying one clip to one of the straps 14 and the other clip to one of the straps 14'. The cover is thus adapted to hold books of different heights at the same time, and if the aggregate thickness of the books is less than the length of the intermediate portions of the straps, the clips may move in the direction of the length of the straps without being detached from the latter.

Clips of the form shown by Fig. 7 would be preferable if it were desirable to detach them easily; but if the assemblage is likely to receive rough handling, or if for any other reason it should be desirable to have the clips more securely fastened to the straps, the form of clip shown by Fig. 8

would be preferable. The latter clip may be applied as readily as that shown by Fig. 7, but the operation of detaching it would be more difficult, because it would be necessary to force the legs apart prior to withdrawing the clip.

I consider the hump of the clip and its coaction with the anchoring strap one of the essential features of this invention, and I consider the provision of three or more anchoring straps, whereby books of different heights may be secured in the cover element, another essential feature of the invention.

I have explained that the end portions of the straps 14, 14' are anchored to the back 10. The significance of this arrangement is that the freedom of the leaves 11, 11 to open is not impaired. Consequently the cover will open fully without any normal tendency to close, and the book or books that are secured to the cover will be held in contiguous relation to the back at all times, regardless of whether the leaves 11, 11 are opened or closed.

I claim:

1. A cover-holder for books, comprising a cover element having a back and hinged leaves, three or more straps extending transversely across the inside of said back, the end portions of said straps being anchored to said cover element and the intermediate portion of each being loose, and a plurality of spring metal clips each having two legs and a portion connecting the latter, each of said clips being adapted to embrace one of said straps and the back of a book, substantially as described, said straps being arranged in a series to coact with books of different heights.

2. A cover-holder for books, comprising a cover element having a back and hinged leaves, straps extending transversely across the inside of said back, the end portions of each said strap having return bends and being anchored to the back, the intermediate portion that connects said return bends of each strap being loose, and means for securing the back of a book to said intermediate portions of two of said straps.

In testimony whereof I have affixed my signature.

GEORGE M. DANIELS.
